UNITED STATES PATENT OFFICE

2,178,894

HEATER

John E. Morgan, Oak Park, Ill., assignor to Sears, Roebuck and Co., Chicago, Ill., a corporation of New York

Application August 17, 1936, Serial No. 96,445

3 Claims. (Cl. 98—2)

My invention relates to heaters which are especially adapted to be mounted in an automobile or other enclosed space.

In an automobile, in cold weather, a person's feet usually become cold first and remain cold, since the coldest air is just above the floorboard. Hence, it is desirable that a heater continually direct warm air downwardly, to displace the cold air and keep the feet warm. However, it is also highly desirable that said downward flow of warm air shall not be at a sacrifice to upper portions of the body, or to the comfort of persons sitting on opposite sides of the heater, since it is usually not enough for body comfort merely that one's feet remain warm.

A special object of my invention, therefore, is to provide, in a heater of the type referred to, a casing adapted to provide a flow of air in a plurality of different directions simultaneously, while at all times directing a flow of air downwardly toward the feet of a person in proximity to the heater.

Another object is to provide a device of the type referred to which will be simple and economical in construction, rugged, and generally satisfactory for the purposes desired.

Numerous other objects and advantages will become apparent as the description proceeds.

Referring now to the drawing forming a part of this specification and illustrating a preferred embodiment of my invention:

Fig. 1 is a front elevation of a heater casing embodying my invention;

Fig. 2 is a sectional view taken substantially along the line 2—2 of Fig. 1, certain portions of the heater being shown dotted; and

Fig. 3 is a sectional view taken substantially along the line 3—3 of Fig. 1.

The heater casing shown in the drawing comprises a dished member 10 which may conveniently be a casting, having a front wall 12, side walls 13, 13, a top wall 14, and a bottom wall 15.

Adjacent the lower wall 15, I provide a plurality of openings or louvres 18. Said louvres are preferably elongated and the casing curved adjacent thereto, as seen in Fig. 2, so that air may be directed therethrough downwardly and forwardly of the casing.

The casing 10 is also provided with a substantially circular flange 20 defining a front opening. Seated in said opening is a door indicated generally by the number 22 and comprising a substantially circular rim 23 having a retaining flange 24 slidably seated against the flange 20, and

a flange 25 lying substantially in the plane of the front wall 12 of the casing.

The rim 23 is retained against inward movement by means of spring clips 27, secured to the front wall 12 of the casing by suitable means such as screws 28 or the like engaging blocks 29, the latter being soldered to the inside of the front wall 12 or cast integrally therewith. The door 22 is of a compound nature, comprising a plurality of separate, individually hinged doors 22a, 22b, 22c, 10 and 22d. Said doors are mounted by means of perforated ears 30, integral with said doors, secured by headed studs 31 to similar ears 32 struck out from the rim 23, as clearly shown in Figs. 1 and 3. Each of said hinged doors is provided with a handle 34, whereby each of said doors may individually be rotated about its hinges. A stop 33 struck out from the rim 23 limits the movement of door 22d.

The compound door 22 may likewise be rotated 20 as a unit by means of a manipulating member or handle 36, secured to the rim 23.

The heating element may be of any suitable design. I have shown merely for purposes of illustration a conventional type of hot water heater comprising headers H and H', fluid conducting members I extending between said headers, heating fluid being conducted to and from the respective headers by means of pipes P and P'. Air is circulated through the heat exchange elements I by means of a fan F operated by means of a suitable motor M.

It is believed that the operation of the device will be obvious from what has gone before. A current of air will, of course, be projected through 35 the heat exchange members arranged in the casing by means of the fan, and the heated air will at all times be projected outwardly and downwardly through the louvres 18, so that the lower extremities of a person in proximity to the heater 40 may continually be bathed in warm air. If desired, the door 22 may be kept entirely closed so that a maximum of air will be projected through the openings 18. On the other hand, if desired, the door 22 and the separate elements 22a, 22b, 45 22c, and 22d, may be adjusted so as to project a current of air in substantially any desired direction, by means of the separate hinging of said elements in conjunction with the rotatable mounting of the door 22 as a whole. Thus, 50 heated air may be projected either downwardly, upwardly, or laterally to the right or left, as desired.

Various changes coming within the spirit of my invention may suggest themselves to those skilled 55

in the art, and hence I do not wish to be limited to the specific embodiments shown or uses mentioned, except to the extent indicated in the appended claims, which are to be interpreted as broadly as the state of the art will permit.

5 I claim:

1. In a device of the class described and in combination, a heater casing having top, bottom, front, and side portions, and having a plurality of permanently open elongated openings in the lower front and bottom portions, whereby a current of air may be directed forwardly and downwardly of said casing, and a universally adjustable closable vane for directing a flow of air in 10 any desired direction outwardly from said casing.
2. In a device of the class described and in combination, a heater casing having a plurality of elongated openings in the front and bottom walls 15

of said casing for directing the flow of air forwardly and downwardly from said casing, said casing having a circular port in the front wall thereof, a member arranged in said port for rotation in the plane of said wall, and a vane hingedly mounted in said member.

- 5 3. In a device of the class described and in combination, a heater casing having front, side, top and bottom walls, a universally adjustable closable vane in the front wall for directing a flow of air in any desired direction outwardly from said casing or alternatively for shutting off said flow, and said casing having a plurality of slots in the lower face of the front wall and in said bottom wall for directing a flow of air outwardly and downwardly from said casing.

JOHN R. MORGAN.
